(57) **CLAIM**

The ornamental design for a nose and ear clearing device, substantially as shown and described.

DESCRIPTION

FIG. 1 is a top perspective view of a nose and ear clearing device according to the invention;

FIG. 2 is a top plan view thereof;

FIG. 3 is a first side elevational view thereof;

FIG. 4 is a second side elevational view thereof;

FIG. 5 is a first end view thereof; and,

FIG. 6 is a second end view thereof.

The broken line portions of the drawing figures are included to show unclaimed subject matter only and form no part of the claimed design.

The “oogiebear” lettering shown in broken lines forms no part of the claimed design. OOGIEBEAR® is a registered trademark owned by Nina D. Farzin.

1 Claim, 2 Drawing Sheets
